UNITED STATES PATENT OFFICE.

EDWARD N. JACOBI, OF MILWAUKEE, WISCONSIN, ASSIGNOR TO BRIGGS & STRATTON COMPANY, OF MILWAUKEE, WISCONSIN, A CORPORATION OF WISCONSIN.

LIGHTING AND IGNITION SWITCH.

Application filed May 24, 1919. Serial No. 299,504.

To all whom it may concern:

Be it known that I, EDWARD N. JACOBI, a citizen of the United States, and resident of Milwaukee, Milwaukee County, Wisconsin, have invented new and useful Improvements in Lighting and Ignition Switches, of which the following is a description, reference being had to the accompanying drawings, which are a part of this specification.

10 This invention has for its object to provide a switch for controlling the lighting and ignition circuits of automobiles or for controlling other circuits wherein it is desired to prevent the operation of the switch 15 by locking means.

Another object of the invention is to provide a lighting switch handle with a lock containing a key-operated lock barrel and provide an ignition switch operated by the 20 lock barrel and permitting the range of movement of the lighting switch without disturbing its condition.

Another object of the invention is to provide a switch mechanism of this type occupying small space and of a comparatively 25 inexpensive construction.

A more particular object of the invention is to provide such a switch structure that will be more durable.

30 With the above and other objects in view the invention consists in the switch as herein claimed and all equivalents.

Referring to the accompanying drawings in which like characters of reference indicate the same parts in different views:

Fig. 1 is a front view of a switch constructed in accordance with this invention;

Fig. 2 is a back view thereof;

Fig. 3 is a sectional view;

40 Fig. 4 is a back view with the terminal head and ignition switch removed;

Fig. 5 is a similar view on the sectional plane of line 5—5 of Fig. 3;

Fig. 6 is a sectional view showing the inner face of the terminal head;

Fig. 7 is a view showing the inner end of the switch handle and the stop for limiting the movement of the lock barrel;

Fig. 8 is a sectional view of the parts operated by the key;

Fig. 9 is a perspective view of the disconnected parts operated by the handle;

Fig. 10 is a view of the lighting switch spider;

Fig. 11 is a perspective view of the eccentric; and

Fig. 12 is a perspective view of the spring seat.

In these drawings 10 indicates a switch handle which has a circular base provided with a reduced annular shoulder 11 rotatably fitting in the central opening of a disk-shaped dial plate 12. The dial plate 12 has its outer edge turned downwardly to form a flange 13 and extensions of this flange at 15 regular intervals form downwardly projecting ears 14.

The shallow cylindrical switch case 15 has an outwardly extending flange 16 provided with openings to receive the ears 14, while 20 the flange 13 of the dial plate bears on the flange 16. The details of construction of the switch case and its connections are covered in my co-pending application for switches, Serial No. 292,836, filed April 26, 25 1919.

Connecting studs 23, threaded in a tapped ring 21 confined between the flange 16 of the switch case and the dial plate 12, serve to clamp a disk-shaped terminal head 24 to 30 the end of the switch case. In the terminal head 24 are contact studs 26 forming binding posts at their outer ends for connection with terminal wires, not shown. The inner ends of the contact studs lie flush with the 35 surface of the terminal head and are recessed to receive the convex ends of the arms of a contact spider 27 which is carried by the handle 10 and constitutes a lighting switch. Other contacts 28, which are 40 arc-shaped and are concentric with the axis of the casing and pass through the terminal head, are engaged by a contact plate 29 operated by a lock barrel in the handle, as will be later described, to constitute an ignition 45 switch. The edges of the contacts 28 lie flush with the surface of the terminal head as do the inner ends of the contact studs 26 so that all may be dressed at the time of 50 grinding the surface of the terminal head. 100

The various parts of the driving and insulating connection for the contact spider are shown in Fig. 9. A thrust plate 30 in the form of a metal disk fits against the bottom of the handle 10 and bears at its 55 edge against the inner surface of the edge of the dial plate 12. A similar disk 34 of insulating material fits on the bottom of the 60

thrust plate. Then comes a driver 35 in the form of a metal ring with projections carrying downwardly extending ears 36 to pass through slots in projections 37 of the double spider 27 which comes next. Finally a spider clamp 38 of insulating material fits beneath the double spider and is provided with projections 39 containing slots through which the ears 36 pass. Certain of said projections on the clamp also have openings through which screws 40 pass so as to clear the spider and its driver and enter through openings in the insulating plate and thrust plate to thread into openings 41 in the bottom of the handle. The spider is thus carried by the handle though insulated from it and the handle is securely held within the dial plate though permitted to turn. The turning movement of the handle is limited by a projection 42 on the edge of the opening of the dial plate projecting into a recess in the bottom of the handle and engaging shoulders 43 at the ends thereof, as seen in Fig. 5.

25 A cylindrical lock barrel 44 is rotatably mounted in a central opening or bore through the handle and carries tumbler slides 45 which may project into side recesses in the handle as usual to prevent the turning of the lock barrel, but which may be drawn within the lock barrel when a key 46 is properly positioned therein. The arc of movement of the lock barrel may be determined by a stop plate 47 keyed thereon and having projection to strike against projections 48 on the bottom of the handle.

40 A coupling or connector 49 is mounted on the end of the lock barrel 44 by having openings 50 fitting over the ends of dowel projections 51 of the lock barrel and by having a lug 52 fitting in a recess 53 of the lock barrel, and while its major portion is cylindrical and concentric with the lock barrel so as to pass through the registering central 45 openings in the disks 30 and 34, driver 35, double spider 27 and clamp 38, its upper portion of larger diameter forms an eccentric 54 fitting within an elongated opening in a lock bolt 55. The lock bolt 55 is contained within 50 a recess in the end of the handle with its ends sliding in grooves thereof so that, as it is shifted longitudinally by the turning of the eccentric, one end is adapted to enter one of a number of notches 56 in the edge of the 55 dial plate to prevent the operation of the lighting switch handle in any of the three positions thereof.

60 A cup-shaped contact plate driver 57 of insulating material receives the end of the coupling 49 and has a groove in the bottom of its cavity fitting on the transverse flange 58 on the end of the coupling so as to be compelled to turn therewith. A spring retainer 59 has its central disklike portion bearing on the end of the driver 57 and its ends

extending upwardly in opposite grooves in the sides of the drivers and the flange at the upper end thereof where said ends extend outwardly to form spring seats for a coil spring 60 which bears on the contact plate 29. 70 The contact plate 29 has a central opening to receive the driver 57 with inwardly projecting lugs 61 fitting in opposite grooves in the sides of the driver so as to form a sliding key connection therewith compelling the contact plate to turn with the lock barrel. The contacts 28, on which the ends of the contact plate 29 bear for controlling the ignition circuit, have their inner ends contained within recesses in the inner face of the terminal head 80 so that they are exposed for contacting with the contact plate and are level with the un-recessed portions of the terminal head onto which the ends of the contact plate pass when the key is turned in the lock. 85

The length of the contacts 28 is such that the contact plate may form the bridge from one to the other in any of the three positions of the lighting switch. Also these ends of the connector plate may swing through the 90 arc of movement of the lighting switch handle without engaging the contacts 28 so that the switch may be locked or unlocked in any position of the handle and whenever it is locked the ignition is rendered ineffective. 95 When the ignition depends upon a supply of current from a battery, it is rendered ineffective by opening the circuit so that the contact plate 29 does not bridge across the contacts 28 in any position of the lighting 100 switch when locked, but when the ignition depends upon a magneto it is rendered ineffective by closing or grounding the circuit by the contact plate bridging across the contacts 28 in all positions of the lighting switch 105 when locked. In order that the switch may be adapted for either condition the lugs 61 on the contact plate are positioned at an angle of 45 degrees from the contact ends and it is only necessary to remove the contact 110 plate and reverse it in order to change its relative position by 90 degrees. This adapts it for either closing a magneto circuit or for opening a battery circuit in all locked positions of the switch, while closing the battery 115 circuit and opening the magneto circuit in all unlocked positions of the switch.

As seen in Fig. 2, one of the arc-shaped contacts 28 has connection with a terminal stud 26 and the other has a connector strap 120 62 pivotally mounted thereon and adapted to be connected either with the terminal stud 26 which is intended to take the battery connection or with an ear 63 on the edge of the switch case, which is intended to have a 125 grounding connection in any suitable manner as through a metal cowl board or by direct connection. A pivotal connection for the connector strap 62 is made by a rivet 64 which clamps the contact segment 28 in place 130

and is preferably countersunk beneath the plane of the bottom of the spring seat 59 so as to avoid contact therewith. The contact segment 28, which contacts directly with the 5 terminal stud, has a projection at its edge bent over for this purpose and riveted to the end of the terminal stud in the manner shown in Fig. 3, with side wings bent up to form a wire guard to take the place of the 10 slotted cup-shaped wire guard riveted to the ends of the other terminal stud. A resistor 65 containing a coiled resistance wire may be connected across two of the terminal studs 26 in the manner shown in Fig. 2 to introduce 15 a dimming resistance in the headlight circuit when separate small headlights are not used. The usual stamped designations for the terminal studs are shown in Fig. 2 as Ign for ignition, Bat for battery, Rear for taillight, 20 S head for small headlight, and L head for large headlight.

In the operation of the switch the spider 27 may be moved by turning the handle 10, on which it is mounted, so as to contact 25 with such terminal studs as to effect the desired connections for the various conditions preferably indicated by marks appearing on the dial plate 12, as "Off", "Dim" and "On". With the arrangement as shown, the lighting 30 switch in the "Off" position makes no connection with the battery contact and consequently none of the lights are lighted. In the "Dim" position connection is made with the "Battery", the "Rear" contact and the 35 "S head" contact so that the taillight is lighted and if small headlights are used they are lighted, but if no small headlights are used the large headlights are dimmed by the passage of the current through the resistor from the "Rear" contact to the "L 40 head" contact. In the "On" position of the lighting switch contact is made with the "Battery", the "Rear" contact and the "L 45 head" contact so that the taillight and the large headlights are lighted. In any of these positions of the lighting switch the ignition switch plate 29, which moves with the handle, may be in either a position in 50 which it bridges across the contact segments 28 or a position in which it bears on the insulating portions of its path of travel, according to whether battery ignition or magneto ignition is used. It may also be turned a quarter turn relative to the switch 55 handle by the turning of the lock barrel by means of the key. Thus by turning the key to the position in which it can be removed, the lock barrel is so turned as to move the ignition contact plate 29 to a position in which 60 it will render the ignition ineffective in either case, and when the key is restored and the lock barrel turned for again unlocking the switch, the ignition switch plate is returned to render ignition effective.

65 If it is desired to lock the ignition switch

only, the locking bolt 55 may be removed and then the lighting switch may be turned to effect any desired change in the lighting arrangement, whether the ignition switch is locked or unlocked.

70

The switch of this invention is adaptable to suit varying requirements so that both lighting switch and ignition switch may be locked or the lighting switch only; so as to control separate small headlights or dim 75 large headlights through the introduction of a resistor; and so as to control either battery or magneto ignition.

What I claim as new and desire to secure 80 by Letters Patent is:

1. In a lock switch, a suitably mounted switch handle capable of turning through an arc of movement, a lock barrel mounted in the switch handle and capable of turning through an arc of movement relative to the 85 handle, a switch member having connection with the lock barrel for movement therewith either by the turning of the handle or the relative turning of the lock barrel, contacts engaged by said switch member in one arc 90 of movement thereof, and means whereby the position of the switch member may be changed with respect to the lock barrel for causing the contacts to be engaged by the switch member in the other arc of movement 95 thereof.

2. In a lock switch, a switch handle capable of turning through an arc of movement, a lock barrel mounted thereon and movable therewith and capable of turning through an arc of movement relative thereto, a switch member connected with the lock barrel, contacts engaged by the switch member in one arc of movement thereof, and means for changing the position of the 100 switch member with respect to the lock barrel for causing it to engage the contacts in the other arc of movement thereof.

3. In a lock switch, a switch handle turning through an arc of movement, a lock barrel therein turning therewith and turning independently through an arc of movement, a switch member having a key connection with the lock barrel and having switch arms 110 at an angle to the key connection whereby 115 the position of the switch arms is changed by reversing the switch member, and contacts engaged by the switch arms in one arc of movement thereof and engaged by the switch arms in the other arc of movement 120 when the switch member is reversed.

4. In a lock switch, a switch handle turning through an arc of movement, a lock barrel mounted therein and turning therewith and also turning independently through an arc of movement, a driver of insulating material connected with the lock barrel, a switch member surrounding the driver and splined thereon, a spring 125 surrounding the driver and bearing on the 130

switch member, and contacts engaged by the switch member during one arc of movement thereof.

5. In a lock switch, a switch handle turning through an arc of movement, a lock barrel mounted therein and turning therewith and turning independently through an arc of movement, a driver connected with the lock barrel, a switch member splined on the driver, a U-shaped spring seat let into the driver, a spring surrounding the driver and bearing on the spring seat and on the switch member, and contacts engaged by the switch member in one arc of movement thereof.

6. In a switch, an insulating terminal head, arc-shaped contacts passing through the terminal head with their arc-shaped edges flush with the face of the terminal head and spaced therefrom within a recess in said face, and a rotatable spring-pressed switch plate bearing on the face of the terminal head and on the edges of the contacts.

7. In a lock switch, a switch handle mounted to turn, a lock barrel mounted in the switch handle, a connector having a driving connection with the lock barrel, a cam on the connector, a lock bolt slideable in the handle and operated by the cam, a stationary part engaged by the lock bolt for locking the handle, a driver having driving connection with the connector, a switch member mounted on the handle, a switch member mounted on the driver, and a terminal head having contacts engaged by the switch members.

8. In a switch, a switch case having a front plate provided with an opening, a switch handle rotatably mounted in the opening of the front plate, a thrust plate on the switch handle bearing against the inner face of the front plate, a contact spider, a driver having ears passing through

the spider, an insulating clamp plate fitting against the spider and receiving the lugs of the driver, screws passing through the clamp plate and into the handle for clamping the spider to the handle, and an insulating plate between the thrust plate and the driver.

9. In a combination lighting and ignition switch, a lighting switch mechanism having contact studs one of which is adapted to have a battery connection, an ignition switch mechanism having contacts, a ground connection, and a connector pivotally mounted on one of the ignition switch contacts and adapted to connect with the battery contact with the lighting switch or with the ground connection.

10. In a switch, an insulating terminal head containing a slot, a sheet metal contact member secured to the back of the terminal head and passing through the slot with its edge forming a contact, and a switch member engaging the contact.

11. In a switch, an insulating terminal head having arcuate slots, sheet metal contact members secured to the terminal head and passing through the slots with their inner edges forming arc-shaped contacts, and a switch member bearing on said arc-shaped contacts.

12. In a switch, an insulating terminal head provided with a slot therethrough, a sheet metal contact member riveted to the back of the terminal head and passing through the slot with its edge forming a contact on the face of the terminal head, and a switch member engaging said contact.

In testimony whereof, I affix my signature, in presence of two witnesses.

EDWARD N. JACOBI.
